UNITED STATES PATENT OFFICE

2,358,982

ADJUSTABLE MOUNTING FOR LIQUID
FUEL BURNERS

John D. Lewis, Youngstown, Ohio, assignor to
Carnegie-Illinois Steel Corporation, a corpora-
tion of New Jersey

Application November 16, 1942, Serial No. 465,787

4 Claims. (Cl. 158—2)

This invention relates to improvements in adjustable mountings for liquid fuel burners of the character employed in open hearth furnaces and the like.

Such burners may employ liquid fuel, such as tar, and generally include an elongate tube or pipe supported externally of the furnace and extending inwardly to direct the flame thereof upon the bath of metal. Due to the location of said burners above the working floor and the crude support thereof from the buckstays of the furnace, they are difficult to adjust for proper direction in relation to the bath, and their manipulation necessitates exposure of the workman to excessive heat.

It is the principal object of my invention to provide an adjustable mounting for such burners having universal movement capable of being easily and readily adjusted without the difficulties aforesaid.

My invention contemplates a universal mounting accessible to the workman and operable by a simple bar or lever, said mounting also being capable of adequately supporting the elongate burner by its relatively short externally projecting portion only.

Additional objects and advantages will become apparent from the following description taken in connection with the accompanying drawings wherein:

Fig. 1 is a vertical section through a portion of an open hearth furnace showing a burner adjustably mounted therein by an embodiment of the invention;

Fig. 2 is an enlarged plan view of the adjustable burner mounting of Fig. 1;

Fig. 3 is a sectional view taken on the line III—III of Fig. 2; and

Fig. 4 is an enlarged section taken on the line IV—IV of Fig. 3.

Referring to the drawings, A designates an open hearth furnace containing a bath of molten metal B. A burner C for the combustion of liquid fuel, such as tar, is directed inwardly toward the bath B from outside the furnace, said burner usually including an elongate tube or pipe, the major portion of which is disposed inside the furnace away from external support.

My improved mounting for such a burner is generally indicated at D, secured to the buckstays 2 of the furnace. In addition to the rigid support provided thereby, the mounting D is capable of adjustment to move the burner C horizontally and vertically in order to properly position the orifice thereof in relation to the bath B.

Said mounting includes a base or frame 3 comprising an angle member extending horizontally between and secured to adjacent buckstays 2, said member having bearing plates 4 vertically slotted for vertical adjustment on the buckstays, as by means of bolts 5. The upper horizontal leg of the angle member 3 is longitudinally slotted at 6 for a substantial distance between the buckstays for purposes hereinafter described. Spaced apart sleeve bearings 7 are secured to the upper face of the frame 3 for slidably and rotatably supporting a tubular shaft 8, parallel with said slot 6, said shaft carrying the burner carriage.

15 The burner carriage includes a slide 9 welded to a pair of spaced sleeves 10 slidable on the shaft 8, said slide being in the form of a plate depending from and between said sleeves through the slot 6 in the frame 3. Beneath said 20 upper flange of the frame 3, the slide is provided with a central threaded boss 11 engaging the threaded terminal of a screw 12 rotatably supported at its other end in a bearing flange 13 secured to the frame 3, said screw extending parallel with the slot 6 in said frame.

25 The carriage also includes a table 14 fixed to the shaft 8 between the sleeves 10 thereon, said table being centrally apertured to receive the threaded stud 15 of a burner support 16 rotatable with said stud on the table, a locking nut 17 being provided to secure the support to the table. The axis of said stud 15 is disposed at right angles to the axis of the shaft 8. Support 16 is provided with a burner clamp including a lower fixed V-jaw 18 and an upper inverted V-jaw 19 movable in relation to the fixed jaw 18 to grip the burner C therebetween so that the latter extends transversely of the support 16.

30 The movable clamp member is pivoted at 20 to the support 16, and on the opposite side thereof is slotted at 21 to receive a stationary vertical locking post 22 on said support, the latter being slotted at 23 in coaxing relation with the entrance of the post in slot 21, whereby the jaws 45 may be secured and wedged in gripping engagement with the burner C by the insertion of a tapered key 24 in slot 23 over the adjacent portion of jaw 19.

35 For the purpose of further securing the burner C, particularly for counteracting the weight of the long inwardly projecting portion of said burner, and also for adjustment of the burner, I provide an adjustable link or turnbuckle 25 having one end thereof pivotally secured to a 50 clamp 26 positioned on the outer end of the burner

C in spaced relation to the mounting of the latter on the carriage. The other end of the turnbuckle 25 is pivotally secured to a clevis 27 pivoted at right-angles to the said attachment of the turnbuckle with said clevis to a projecting lug 28 centrally secured to the carriage slide 9, said turnbuckle being adjustable by means of its threaded sleeve 29 having a convenient hand-wheel 30 secured thereto.

In operation, the frame 3 of burner mounting D is secured to the buckstays 2 of the furnace at a suitable elevation with relation to the burner opening E in the furnace by the slotted plates 4 and bolts 5. The burner C is secured to the carriage by the clamp 18-19, and the turnbuckle 25 is adjusted to dispose the burner at the proper inclination in a vertical plane with respect to the bath B, the carriage table 14 pivoting about the horizontal axis of the shaft 8 upon adjusting the turnbuckle.

If it is desired to translate the burner laterally in a horizontal direction, for adjustment thereof with relation to the bath B, the operator may rotate the feed screw 12 to translate the entire carriage by sliding movement of the shaft in the bearings 7 on the frame 3. Also, the burner C may be adjusted laterally about the pivotal axis of the table 14, upon loosening the nut 17 and moving said burner and table upon the stud 15.

Means are provided for conveniently effecting the aforesaid adjustments by the operator, as by means of bars or pipes indicated at 31 in Fig. 2, said means including short pipe sections or sleeves 32 affixed to feed screw 12, table 14 and nut 17. By insertion of the bars 31 in said pipe sections 32, the operator may stand a suitable distance from the burner mounting while adjusting the latter, whereby he will not be subjected to the high temperatures immediately adjacent said mounting. It will thus be seen that I have provided an adjustable mounting for burners of the character described, which mounting has universal adjustment to enable the convenient positioning of the burner sleeves in relation to the bath of molten metal B.

Various modifications and changes are contemplated within the scope of the following claims.

I claim:

1. The combination with a burner adapted to extend inwardly through a furnace opening, of a supporting frame adapted to be disposed transversely of said burner and opening, a shaft rotatably mounted on said frame and slidably thereon transversely of the burner, a burner carriage including a slide slidable with said shaft, said carriage also having a table rotatable with said shaft, a burner support rotatable on the table, means for securing the burner to said support, means on the frame for adjustably sliding the carriage and shaft, adjustable means connecting the slide and burner for rotating said burner with the carriage and shaft, and means for securing the burner support to the table of said carriage.

2. The combination with a burner adapted to extend inwardly through a furnace opening, of a

supporting frame adapted to be disposed transversely of said burner and opening, a burner carriage having a slidable portion and a rotatable portion mounted on the frame, means for clamping the burner transversely of the rotatable portion of the carriage with the outer end of said burner extending beyond said carriage, adjustable means connecting the said outer end of the burner with the slidable carriage portion for rotating the burner with the rotatable carriage portion, and means carried by the frame and engaging the slidable carriage portion for adjustably sliding the burner and carriage on said frame in a direction transversely of said burner.

3. The combination with a burner of the character described, of a horizontal supporting frame therefor, said frame being longitudinally slotted, a shaft mounted for sliding travel on the frame parallel with the slot therein, said shaft also being rotatable about its longitudinal axis, a burner carriage secured to the shaft, a sleeve freely mounted on the shaft on either side of the carriage and a slide extending downwardly from said sleeves through the frame slot, an adjusting screw rotatably mounted in the frame parallel with said slot and having threaded engagement with a coacting portion of the slide, said carriage also having a table rotatable thereon, a burner support rotatable on the table about an axis at an angle to the axis of said shaft, adjustable means securing the burner support against rotation with respect to the table, a clamp on the burner support for securing the burner transversely thereof with the outer end of said burner extending beyond the carriage, and a turnbuckle connecting said outer end of the burner with the carriage slide for pivotal adjustment of the carriage and burner about the shaft axis.

4. The combination with a burner of the character described, of a horizontal supporting frame therefor, said frame being longitudinally slotted, a shaft mounted for sliding travel on the frame parallel with the slot therein, said shaft also being rotatable about its longitudinal axis, a burner carriage secured to the shaft, a sleeve freely mounted on the shaft on either side of the carriage and a slide extending downwardly from said sleeves through the frame slot, an adjusting screw rotatably mounted in the frame parallel with said slot and having threaded engagement with a coacting portion of the slide, said carriage also having a table rotatable thereon, a burner support rotatable on the table about an axis at an angle to the axis of said shaft, adjustable means securing the burner support against rotation with respect to the table, a clamp on the burner support for securing the burner transversely thereof with the outer end of said burner extending beyond the carriage, a turnbuckle connecting said outer end of the burner with the carriage slide for pivotal adjustment of the carriage and burner about the shaft axis, and receiving sockets attached to the screw and to the means securing the burner support against rotation for manipulation thereof by the insertion of a bar therein.

JOHN D. LEWIS.
